Des. 198,846
Patented Aug. 11, 1964

198,846

ARCHITECTURAL SCREEN WALL UNIT

Erwin F. Hauer, Wooding Hill Road, Bethany, Conn.

Filed June 10, 1963, Ser. No. 75,290

Term of patent 14 years

(Cl. D18—2)

FIG. 1

FIG. 2

FIG. 3

FIG. 4

FIG. 1 is a perspective view of an architectural screen wall unit showing my new design;

FIG. 2 is an elevational view thereof, it being understood that the wall has the same appearance from the front and back;

FIG. 3 is a side edge view thereof, it being understood that the wall has the same appearance from either side edge; and

FIG. 4 is a top edge view thereof, it being understood that the wall has the same appearance at the bottom edge.

I claim:

The ornamental design for an architectural screen wall unit, substantially as shown and described.
